UNITED STATES PATENT OFFICE.

GUIDO E. LOB, OF CHICAGO, ILLINOIS.

PNEUMATIC CONVEYER.

1,184,860.

Specification of Letters Patent. Patented May 30, 1916.

Application filed June 25, 1914. Serial No. 847,181.

To all whom it may concern:

Be it known that I, GUIDO E. LOB, a citizen of the United States, residing at Chicago, in the county of Cook and State of Illinois, have invented certain new and useful Improvements in Pneumatic Conveyers, of which the following is a specification.

The invention relates to pneumatic conveyers in general, and to the discharge 10 spouts thereof in particular.

In the handling of grain, particularly grains which are moist, the discharge spouts of conveyers are liable to become clogged or closed, thereby decreasing the efficiency 15 of the conveyer.

It is the object of the present invention to overcome this disadvantage by providing a discharge spout which will positively eject all grain therefrom and wherein any accumulation of grain will be impossible.

With the above and other objects in view, this invention consists in the construction, combination, and arrangement of parts all as hereinafter more fully described, claimed, 25 and illustrated in the accompanying drawings, wherein:

Figure 1 is a side elevation of the discharge spout forming the subject-matter of the present invention, illustrating, in dotted 30 lines, the pivotal movement of the spout; Fig. 2 is a central vertical section thereof; Fig. 3 is a horizontal section taken along line 3—3, Fig. 2; Fig. 4 is a similar view along line 4—4, Fig. 2; Fig. 5 is a vertical 35 section taken along line 5—5, Fig. 2; Fig. 6 is a side elevation of a modified form of the spout; Fig. 7 is a central vertical section thereof; and Fig. 8 is a sectional view along line 8—8, Fig. 7.

Reference being had more particularly to the drawings, Figs. 1 to 5, inclusive, 40 indicates the flexible discharge tube of a conveyer of a general type. This discharge tube 10 is surrounded by a collar 11 to which 45 is secured a rigid tube 12 by a collar 13 co-operating with the collar 11. The lower end of the tube 12 has an angle iron 14 secured thereto and conforming to the contour thereof, one of the flanges extending 50 horizontally from said tube. A second, or as will be seen, an outer, tube 15 is aligned with and abuts the tube 12, said tube 15 be-

ing secured thereto for relative bodily movement. This attachment is accomplished by an angle iron 16 secured to the upper terminal of the tube 15 which is provided with a rib 16^a that embraces the horizontal arm of the angle iron 14, said rib resting in substantially the same vertical plane as said horizontal arm. A metal ring 17 is secured 55 by screws or other suitable means to the upper surface of the rib 16^a of the angle iron 16 and extends over the horizontal arm of the angle iron 14, resting flush thereon (see Fig. 2). A wear ring 18 of fiber or other 60 adaptable material is interposed between the ring 17 and the rib 16^a and horizontal arm of the angle iron 14, being so provided to take up wear between the elements which may be caused by the relative bodily movement thereof. It is manifest that this second or outer tube 15 is by this construction 65 so attached to the tube 12 that it may rotate with respect thereto and at the same time maintain its alinement and connection therewith.

An inner tube 19 is located within the outer tube 15 and extends throughout the entire length thereof. This inner tube 19 is spaced from and supported by the outer 70 tube 15 through the medium of the spacing and reinforcing rings 20 which are interposed between said tubes. The inner tube 19 in combination with the outer tube 15 forms an air chamber 21 below the lower 75 ring, whereby air may be directed to the spout or nozzle for forcing grain therefrom, as will be hereinafter more fully described.

An air-distributing casing 22, in the shape of an inverted truncated cone, surrounds the 80 outer tube 15 somewhat below the plane of the lower ring 20. To support this casing 22 on the outer tube 15, the same is provided with the inwardly-extending flanges 23, and 24 at the upper and lower ends 85 thereof respectively, which extend to the tube 15 and rest flush thereagainst. The outer tube 15 just above and below the casing 22, is surrounded by a band 25 which is provided with an outstanding rib 26. 90 These ribs 26 rest parallel and in very close proximity to the adjacent or co-operating flanges 23 and 24. These balls 27 are interposed between each flange 23 and 24 and

its coöperating rib 26. A leather gasket 28 is held over joint between each flange 23 and 24, and its coöperating band 25 by the metal rings 29 and prevents the escape of air from the casing 22. By this construction it is possible to rotate the casing 22 on the outer tube 15 without destroying any of its connections or changing its position longitudinally with respect to the tube 15.

- 10 The upper flange 23 is pierced by an opening 30 through which air enters the casing 22. This inlet opening 30 extends around about one-half of the tube 15, and is entirely surrounded or embraced by an air-supply casing 31 which conforms to the shape of the inlet opening 30 at its base and curves upwardly to the supply pipe 32. The supply pipe 32 is secured to the casing 31 in any suitable manner so that it will move 15 with the casings 31 and 22 when they are moved about the tube 15. Air under pressure is fed from the pipe 32 to the supply casing 31, from which it enters approximately one-half of the distributing chamber

20 22 through the inlet opening 30. From the distributing chamber or casing 22, the air, still under pressure, passes to the air chamber 21 between the tubes 15 and 19, through the openings 33 formed in the outer tube 15 for that purpose. The air, under pressure, is then directed to the discharge spout as will be hereinafter described.

- 25 The extreme lower end of the outer tube 15 is surrounded by a collar 34, which is provided with the horizontal flange 35 and the opposed ears 36 and 37. A curved spout tube 38, having a horizontal flange 39 at its upper end which normally rests flush with 30 the flange 35 of the collar 34, is located at the ends of the tubes 19 and 15 so that the passage therein alines with the passage in the tube 19. By means of pivot pin 40 one side of the spout tube 38 is permanently 35 hinged to the collar 34 and consequently to the outer tube 15 at a point adjacent to the ears 37. A bolt 41 is pivoted to the pivot pin 40 and is arranged to swing between the ears 36 and, through the instrumentality of 40 the thumb nut 42 bearing on said ears, take up the wear about the pivot pin 40; thus insuring a tight connection between that side of the spout tube 38 and the tubes 15 and 19. Diametrically opposite to the hinge 45 40 is a bolt 43 pivoted between the ears 44 on the spout tube 38, and provided with a thumb nut 45. This bolt is arranged to swing between the ears 37 of the collar 34 so that the nut 45 thereof will bear against 50 the upper surfaces of said ears. In this manner the free side of the sleeve spout 38 may be drawn and secured to collar 34, thus insuring a positive connection between that side of the tube 38 and the tubes 15

55 and 19. By this construction it is possible to swing the spout tube 38 away from the tubes 15 and 19 by loosening the thumb nut 45 and releasing the bolt 43 from the ears 37, it being unnecessary to adjust the bolt 41 or thumb nut 42 in any manner except 70 to take upper wear around the hinge or pivot pin 40.

On the interior of the spout tube 38 is an inner wall or partition 46 which extends around substantially one-half of said spout tube (see Fig. 5). A centrally-disposed longitudinal rib 47, interposed between the tube 38 and the wall or partition 46, supports and reinforces this wall or partition in such a manner that the air passage 48 formed thereby is unobstructed. The formation of this air passage 48 is such that the upper or inlet end thereof extends completely around the upper end of the spout tube 38 and is alined and connects with the air chamber 21 85 between the tubes 15 and 19; while the lower or outlet end is located at the lower side of the horizontal portion of the tube

38 and adjacent to the reduced spout 49 secured to said tube (see Fig. 2). Manifestly, the air under pressure in the air chamber 21 will be directed into the space 48 and discharged therefrom into the spout 49. The grain passing through the inner tube 19, spout tube 38, and spout 49 is thus 95 acted upon by the air and positively forced through the said spout thereby preventing any accumulation of grain within either the spout 49 or spout tube 38.

In order to support the spout 49 and spout tube 38 after they have elevated to the dotted line position in Fig. 1, a hook 50 is secured to the lower band 25 and coöperates with the staple 51 riveted to the spout 49.

The modified form of discharge spout 105 illustrated in Figs. 6, 7, and 8 is so constructed that the air under pressure, is directed entirely around and through the spout instead of around a portion thereof as in the preferred form shown in Figs. 1 to 5, inclusive. This increases the positiveness with which the grain is ejected and at the same time prevents any accumulation of the grain within the spout. The superstructure of this modified form is identical 110 with that of the preferred form; in other words, the two spout structures are the same to the lower ends of the air-distributing casing 22. Below the point they differ.

A curved spout tube 52 is rigidly attached to the extreme lower end of the outer tube 15 by means of the abutting angle irons 53, one secured to the upper end of the spout 52 and the other to the lower end of the outer tube 15. The inner tube 19 120 is provided with a curved extension 19^a which follows the curves of the spout tube 52 and is spaced therefrom, forming a con-

tinuation 21^a of the air chamber 21. This continuation 21^a extends completely around the interior of spout tube 52 and terminates at the end of said spout tube. As illustrated in Fig. 7, the extension 19^a of the inner tube 19 extends a trifle beyond the end of the spout tube 52 and into the spout 54 which is attached thereto and forms a continuation thereof, thereby directing the air 10 under pressure into the spout.

The spout 54 is pivoted to the spout tube 52 through the instrumentality of a collar 55 on the extreme end of the tube 52 coöperating with a collar 56 on the inner end of 15 the spout 54. A hinge 57 forms a pivotal connection between these collars 55 and 56, while diametrically disposed to said hinge is a bolt 58 pivoted to collar 55 and coöperating with ears 59 formed on the collars 20 56. Threaded on the end of the bolt 58 is a thumb nut 60 which bears against the ears 59 and draws the collars together, thus securing the spout to the spout tube.

Manifestly the spout structure below the 25 tube 12 is bodily movable below said tube in both forms of the invention, thereby making it possible to direct the flow of the grain from the spout in any direction.

I claim as my invention:

30 1. The combination of an inner and an outer tube having an air chamber therebetween, means for supplying air to said chamber, a spout hinged to and coöperating with said tubes, and means for directing the 35 air in said chamber to said spout comprising a side chamber in the spout adapted to connect to the air chamber between the tubes when the spout is operatively connected to said tubes.

40 2. The combination of a tube, a second tube surrounding the same to form an air chamber, means for supplying air to said chamber, a spout hinged to the lower end of and coöperating with said tubes, and a 45 wall within said spout forming an air passage adapted for connection with air space between said tubes when the spout is in co-operating position therewith.

3. The combination of a tube having an 50 air space surrounding the same, of a spout hinged to the lower end of the tube, and means for directing air from said air space to the outlet end of the spout including a side air passage in a portion of the spout.

55 4. In a conveyer, an inner conveyer tube, an outer tube surrounding the inner tube and separated sufficiently to provide a passage for compressed air, a spout having an elbow hinged to the lower end of the conveyer tube and provided with a passage 60 communicating with the air passage between the tubes.

5. In a conveyer, an inner conveyer tube, an outer tube surrounding the inner tube

and separated sufficiently to provide a passage for compressed air, a spout having an elbow hinged to the lower end of the conveyer tube and provided with a passage formed in one side of the elbow and communicating with the air passage between the tubes. 65

6. In a conveyer, an inner conveyer tube, an outer tube surrounding the inner tube and separated sufficiently to provide a passage for compressed air, a spout having an elbow hinged to the lower end of the conveyer tube and provided with a passage formed in one side of and bending around the elbow and communicating with the air 75 passage between the tubes. 80

7. The combination of a conveying tube, of an outer tube surrounding the same, forming an air chamber therewith, a distributing casing surrounding said outer tube, said outer tube being provided with a series of openings forming a connection between said casing and said air chamber, an air supply casing coöperating with said distributing casing, having an extended connection therewith, a spout coöperating with 85 said tubes, and means within said spout for conducting air from the air chamber to the discharge end of said spout and there ejecting it. 90

8. The combination of a conveying tube, 95 of an outer tube surrounding the same forming an air chamber therewith, a distributing casing surrounding said outer tube, said outer tube being provided with a series of openings forming a connection between said 100 casing and said air chamber, an air supply casing coöperating with said distributing casing having an extended connection therewith, a spout coöperating with said tubes, and a wall within said spout terminating 105 adjacent to the discharge end thereof and forming a passage for connection with the air chamber aforesaid.

9. The combination of a conveying tube, 110 of an outer tube surrounding the same forming an air chamber therewith, a distributing casing surrounding said outer tube, said outer tube being provided with a series of openings forming a connection between said casing and said air chamber, an air supply 115 casing coöperating with said distributing casing having an extended connection therewith, a spout having an elbow hinged to said tubes, and means for conducting air from the air chamber aforesaid to the outer 120 end of said spout including an air passage formed in the elbow of the spout.

10. The combination of a conveying tube, of an outer tube surrounding the same forming an air chamber therewith, a distributing casing surrounding said outer tube, said outer tube being provided with a series of openings forming a connection be- 125

tween said casing and said air chamber, an air supply casing coöperating with said distributing casing having an extended connection therewith, and a spout hinged to 5 said tubes having an air passage therein for coöperation with the air chamber aforesaid.

In testimony whereof I have hereunto af-

fixed my name in the presence of two witnesses.
